UNITED STATES PATENT OFFICE.

CARL EDWARD BAUER, OF HAMMOND, INDIANA, ASSIGNOR TO AMERICAN STEEL
FOUNDRIES, OF CHICAGO, ILLINOIS, A CORPORATION OF NEW JERSEY.

TRUCK SIDE FRAME.

1,330,049.

Specification of Letters Patent.

Patented Feb. 10, 1920.

Application filed August 9, 1917. Serial No. 185,243.

To all whom it may concern:

Be it known that I, CARL EDWARD BAUER, a citizen of the United States, and resident of Hammond, in the county of Lake and State of Indiana, have invented certain new and useful Improvements in Truck Side Frames, of which the following is a specification.

This invention relates to railway car trucks and more particularly to side frames therefor.

One of the objects of the invention is to simplify, lessen the cost of, and at the same time strengthen side frames of car trucks.

Another object is to increase the resistance of the yoke portion of side frames against transverse strains set up in starting and stopping cars.

Another object is to provide a novel truck side frame adapted to meet the various requirements for successful commercial operation.

These and other objects are accomplished by providing a truck side frame having in combination spaced tension and compression members, a yoke extending therebetween, and a reinforcing member connected to said yoke and to the compression member.

The invention is illustrated on the accompanying sheet of drawings in which,

Figure 1 is a side elevation, parts being in section, of a truck side frame embodying my invention;

Fig. 2 is a top plan view of the same;

Fig. 3 is a transverse sectional view taken in the plane of line 3—3 of Fig. 1, and

Fig. 4 is a sectional view of the yoke member and coöperating reinforcing member taken in the plane of line 4—4 of Fig. 1.

The various novel features of my invention will be apparent from the following description and drawings and will be particularly pointed out in the appended claims.

Referring to the figures of the drawings, it will be noted that I have provided a truck side frame having a compression member 10 and tension member 11, the same being spaced from each other at their middle portions and having interposed therebetween a central yoke 12. In this particular case the compression member includes two angle bars 13 and 14, the middle portions of which are horizontal and slightly raised, said bars then

extending laterally and downwardly converging toward the outer ends of the tension member 11 to which they are secured. The tension member 11 in this case is preferably of channel section with its flanges extending upwardly toward the compression member. The middle portion of the tension member 11 is curved and its lateral portions extend upwardly and outwardly to points of connection with the compression member.

The yoke 12 which is interposed between the tension and compression members, is preferably of plate material and is rolled into a U-section and the yoke is also in the form of a U. The bottom portion of the yoke 12 rests in the central channel portion of the tension member 11 and is curved in accordance with the curve in the tension member.

The side columns 15 and 16 of the yoke member 12 extend upwardly and pass between the vertical flanges 17 and 18 of the compression angle bars 13 and 14. The upper ends 30 of these columns 15 and 16 extend beyond the vertical flanges 17 and 18 of the compression bars 13 and 14 and their opposite walls are bent in opposite directions to hook over the respective flanges 17 and 18 to relieve the rivets 19 of considerable strain. It will be noted that the rivets 19 pass through the vertical flanges 17 and 18 of the angle compression bars 13 and 14 and also through the upper ends of the side columns of the yoke 12 member 12.

The lateral walls 20 and 21 of the side columns 15 and 16 extend inwardly toward each other and are arranged to receive oppositely extending legs 22 of a U-shaped reinforcing member or auxiliary yoke 23 of T-cross-section. The upwardly extending leg 24 of the reinforcing member 23 extends between the vertical flanges 17 and 18 of the compression bars 13 and 14, rivets 25 passing through said vertical flanges 17 and 18 and also through the vertical leg portion 24 of reinforcing member 23. Rivets 26 also pass through the lateral walls 20 and 21 and the oppositely extending leg portions 22 of the reinforcing member 23 to securely fasten the reinforcing member 23 to the side columns 15 and 16 of the yoke 12. By means of securing the reinforcing member to the side columns 15 and 16 and also to the compression member, a rigid structure is formed

which greatly reinforces the yoke 12 in resisting strains set up during starting and stopping of cars.

It will be appreciated that the opening formed between the side columns 15 and 16 of the yoke is for the reception of a bolster which normally occupies the upper half of the space between said columns 15 and 16 and bears against the lateral faces 27 of the reinforcing member 23. In order that the bolster with its associated brackets (which are not shown) may be passed through the opening between the side columns 15 and 16, the lateral walls 20 and 21 are rolled over to increase the space formed in the lower half of the yoke member. The bolster, as is well appreciated, is held in its normal raised position between the downwardly extending portions of the reinforcing member 23 by a suitable spring or springs, the lower portions of which rest in a spring seat 28 which is received in the lower channel portion of the yoke 12. The tension member 11, yoke 12 and spring seat 28 are connected together by suitable rivets 29.

With this yoke member 12 connected to the tension and compression members as it is, and with its coöperating reinforcing auxiliary yoke member 23 connected thereto and to the compression member, a rugged arrangement is provided adapted to meet the various requirements for successful commercial operation.

It is apparent that there may be modifications of the invention as herein particularly shown and described, and it is my intention to cover all such modifications which do not involve a departure from the spirit and scope of the invention as set forth in the following claims.

I claim:

1. A truck side frame including spaced tension and compression members, a yoke extending therebetween and having one end hooked over said compression member to share the load, and a reinforcing member within and connected to said yoke and to the compression member.

2. A truck side frame including spaced tension and compression members, a main yoke extending therebetween, and a supplemental reinforcing yoke connected to said main yoke and to one of said members.

3. A truck side frame including spaced tension and compression members, a yoke of U-section extending therebetween, and a reinforcing member having flanges which are received by U-portions of the side columns of the yoke for reinforcing the yoke.

4. A truck side frame including spaced tension and compression members, a yoke of U-section extending therebetween, and a reinforcing member having flanges which are received by U-portions of the side columns

of the yoke for reinforcing the yoke and having a portion connected to the compression member.

5. A truck side frame including spaced tension and compression members, means extending therebetween comprising spaced column members hooked over the compression member to share the load, and a reinforcing member between and connected to said column members and to said compression member.

6. A truck side frame including spaced tension and compression members, means extending therebetween comprising column members having flanges and being hooked over the compression member, and a reinforcing member between and connected to said column members between said flanges and connected to said compression member.

7. A truck side frame including a tension member, a compression member including spaced bars, means including column members extending between said tension and compression members and hooked over the latter, and a reinforcing member between and secured to said column members and having a flange secured between the bars of said compression member.

8. A truck side frame including a tension member, a compression member comprising spaced bars, a yoke having column members with flanges and extending between said tension and compression members, and a reinforcing member having flanges secured between the flanges of said column members and having a flange secured between the compression bars.

9. A truck side frame including a tension member, a compression member comprising spaced bars, a yoke having column members with flanges and extending between said tension and compression members, and a reinforcing member having flanges secured between the flanges of said column members and having a flange secured between the compression bars, the upper ends of said column members being hooked over said compression bars to share the load.

10. A truck side frame including spaced tension and compression members, and a yoke extending therebetween and having one end thereof hooked over one of said members to share the load.

11. A truck side frame including a tension member, a compression member having spaced bars, and a yoke extending between said tension and compression members and passing between said compression bars and having the ends hooked over said compression bars to share the load.

Signed at Hammond, Indiana, this 4th day of August, 1917.

CARL EDWARD BAUER.
